GILBERT W. GOODRIDGE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

FUSE-PLUG.

No. 928,642.

Specification of Letters Patent.

Patented June 1, 1909.

Application filed December 22, 1908. Serial No. 468,798.

To all whom it may concern:

Be it known that I, GILBERT W. GOODRIDGE, a citizen of the United States of America, and residing in the city of Bridgeport, in the county of Fairfield and State of Connecticut, have invented a certain new and Improved Fuse-Plug, of which the following is a specification.

My invention relates to electric fuses and particularly to that type of fuse commonly known as the standard Edison fuse plug, the object of my invention being to improve the construction of the same in the particulars below mentioned.

In the accompanying drawings in which a fuse plug of the type described embodying my invention is shown, Figure 1 is a vertical section of the plug with cap removed and with the fuse strip secured only at the lower end; Fig. 2 is a similar section with the upper end of the fuse strip soldered and the cap in place; Fig. 3 is a horizontal section on the lines 3-3, Fig. 2; Fig. 4 is a side elevation of the plug complete; and Fig. 5 is a side elevation of the porcelain alone.

The porcelain employed in the present construction is of the type commonly used in the Edison plug receptacles and comprises a threaded plug end A, in the lower extremity of which the contact X is secured. The usual metallic cap C with insulating disk e is crimped upon the shoulder B. In the customary construction the fuse strip F is carried from the terminal X over the partition

D formed by the recess E and down through the latter to the outer face of the threaded shell G which forms the other terminal of the plug, the shell being offset inwardly into the recess E to facilitate this arrangement. In this position the fuse strip is soldered to the shell on the outside of the latter. This construction however presents several disadvantages. For example when the fuse is blown the heat generated is ordinarily sufficient to melt the solder, and the latter being on the outside of the shell, effectively solders the plug to the receptacle in which it is fitted. This makes it very difficult to remove the blown fuse plug for the purpose of re-

placing it by a fresh one. Again the shell G frequently fits the plug end A loosely—owing to the difficulty in precisely controlling the size of the porcelain during firing. Consequently the only thing which prevents the shell from turning on the plug is the soldered joint between the fuse strip and the shell, the strip being limited in its angular movement by the sides of the recess E. But the strain which is put upon the soldered joint between the strip and shell when screwing the plug down into its receptacle presents a dangerous feature in the plug, since the joint might readily be loosened and even ruptured in this manner. To avoid these disadvantages, I propose to carry the shell up straight to the shoulder b, thus forming of the recess E a well open only at the top. The end of the fuse F being carried down into this well and the solder S poured in, a perfect electrical connection between the shell and fuse strip is secured, while at the same time the solder is kept wholly on the inner face of the shell, and the disadvantage above mentioned in regard to the soldering of the plug to the receptacle upon the blowing of the fuse, is avoided. Furthermore, if the joint between the shell and plug end A be loose, the solder flows into the threads between the porcelain and shell and renders these rigid with relation to each other, in effect soldering them together. All strain upon the joint between the shell and fuse strip is thereby eliminated.

As a whole the fuse plug in this improved form is made as economically as in the past, while it presents a much neater appearance as well as having the advantages pointed out.

I claim as my invention:

1. In a fuse plug of the type described, a hollow insulating body provided with an external shoulder, said body having a downwardly extending recess opening from the interior to a point below said shoulder on the exterior, in combination with a conducting shell on said body forming in connection with said recess body a well opening only into the interior of the latter to receive the end of a fuse strip, substantially as described.

2. In a fuse plug of the type described, a hollow insulating body externally threaded and shouldered, in combination with a shell of conducting material threaded on said body and abutting against said shoulder, said insulating body having a downwardly extending recess opening from the interior to a point below said shoulder on the exterior, in combination with a fuse strip one end of which extends into the well so formed

between said shell and insulating body and solder flowed into said well and communicating crevices between said shell and body to electrically unite said fuse strip to said shell and to rigidly bind said shell and body together, substantially as described.

In testimony whereof I have signed my

name to this specification, in the presence of two subscribing witnesses.

GILBERT W. GOODRIDGE.
